GUN MOUNT

Elmer C. Goebert, United States Army, Philadelphia, Pa., and George W. Beatty, Decatur, Ill.

Application May 11, 1934, Serial No. 725,132

5 Claims. (Cl. 89—40)

(Granted under the act of March 3, 1883, as
amended April 30, 1928; 370 O. G. 757)

The invention described herein may be manufactured and used by or for the Government for governmental purposes, without the payment to us of any royalty thereon.

5 This invention relates to a gun mount.

The principal object of the invention is to provide a light gun mount which may be emplaced on the ground or on a support.

10 A further object is to provide an anti-aircraft gun mount having a novel arrangement whereby a gunner seated in a chair may readily control the movement of the gun in azimuth and elevation.

With the foregoing and other objects in view, the invention resides in the novel arrangement and combination of parts and in the details of construction hereinafter described and claimed it being understood that changes in the precise embodiment of the invention herein disclosed may be made within the scope of what is claimed without departing from the spirit of the invention.

A practical embodiment of the invention is illustrated in the accompanying drawings, wherein:

Fig. 1 is a view in side elevation of the improved gun mount emplaced on an artillery caisson.

25. Fig. 2 is an enlarged view in side elevation with parts broken away.

Fig. 3 is a sectional view on the line 3—3 of Fig. 2.

Fig. 4 is a plan view of the mount with the gun removed.

Figs. 6 and 7 are respectively views in plan and

Fig. 8 is a sectional view on the line 8-8 of Fig. 6 and 7 are respectively views in plan and side elevation of the trigger actuating linkage.

Fig. 9. is a sectional view on the line 9—9 of

40 The mount comprises a base ring 5 having a plurality of bent spokes 6-6 terminating centrally in a tubular pintle 7.

45 A top carriage adapted to be rotatably mounted on the base ring is in the form of a yoke having spaced standards 8-8 connected at their lower ends by a cross-piece 9. A socket 10 on the cross-piece is mounted on the pintle 7 through bearings 11 and 12 (Fig. 9) and is retained in place by means of a nut 13 threaded on the upper end of the pintle.

50 A seat 14 carried by the cross-piece and preferably having arms 15—15 secured to the standards is so arranged that the feet of an occupant will conveniently engage the base ring 5. By
55 means of this engagement the occupant may

easily produce rotation of the top carriage on which he rides.

A cradle 16 for carrying one or more guns 17 which are attached by pins 18-18 is provided at its rear end with a pair of spaced arms 19-19 whose rear ends are mounted on trunnion pins 20-20 in the upper ends of the standards 8. A pair of equilibrators each consisting of telescoping members 21 and 22 and an expandible agent conveniently a spring 23, are provided for counter-acting the unbalanced condition of the cradle. The inner member 21 is attached by a pivot pin 24 to a foot 25 on the lower part of a standard 8 and the outer member 22 is attached by a pivot pin 26 to the arm 19 of the cradle at a point forwardly of the cradle trunnion.

Referring to Fig. 3 the outer member 22 is provided at one end with a slit 27 and this end is embraced by a split clamping ring 28. Apertured lugs 29 and 30, the latter being internally threaded are provided on the split ends of the ring 28. A bolt 31 inserted through the apertured lugs and threadedly engaging the lug 30 is embraced by a spring 32 confined between the lug 29 and the head 33 of the bolt. A nut 34 is placed on the threaded end of the bolt. By means of the clamping ring sufficient friction is maintained between the members 21 and 22 so that the cradle will remain in any position in which it is placed. The ring 28 of one of the equilibrators carries a lug 35 adapted to engage a stop 36 on the corresponding standard 8.

The movement of the cradle about its trunnions is controlled by means of a pair of handles 37—37, each carried by one of the arms 19 of the cradle and depending therefrom substantially perpendicular to the arm. The handles are positioned just inside of the standards 8 and may be conveniently grasped by the occupant of the seat 14.

A linkage 38 including levers 39-40 and 41, is carried by the cradle and permits actuation of the trigger 42 of the gun from a position in the vicinity of the hand-grip 43 of the handle 37.

The gun mount is arranged for travelling by locking the top-carriage against rotation relative to the base ring and by locking the cradle against rotation relative to the top-carriage. An arm 44 (Fig. 5) fixed to the top carriage has a hooked extremity 45 engaging the under side of the base ring 5 and carries a screw bolt 46 which may be turned to engage the upper side of the base ring. 50

A plunger 47 (Fig. 8) mounted in one of the standards 8 is normally urged by a spring 48 55

into a recess 49 in the corresponding handle 37 of the cradle when the cradle is at zero elevation. The plunger is withdrawn from the recess by a lever 50 secured to its outer end by a pin 51 and having a foot 52 whereby it may exert a camming action on the standard 8.

Each of the spokes 6 is provided at its outer end with an inclined socket 53 having internal threads 54 for receiving the threaded stem 55 of a float 56. A handwheel 57 is formed on the float to provide for rotating it. When the gun mount is emplaced on the ground the floats are lowered until they engage the ground. The floats also serve for levelling the mount and may readily be turned by the occupant of the seat.

Referring to Figs. 1, 2 and 5 the gun mount is arranged to be emplaced above the ground on a support, in the present instance, an artillery caisson 58. A convenient method of connecting or attaching the base ring 5 to the support consists in utilizing the tubular pintle 7 for receiving a post 59 (Fig. 9) on the support. The base ring may be readily lifted and applied to or removed from the post.

In the present instance the post is associated with a movable plate 60 which is connected along one of its sides by a hinge pin 61 to a fixed plate 62. The fixed plate 62 is secured by U-bolts 63 to the drawbar 64 of the caisson.

The sides of the plates 60 and 62 opposite to the hinge pin rotatably carry horizontally disposed cylindrical nuts respectively 65 and 66. The nuts 65 and 66 are provided respectively with diametral apertures having opposite threads 67 and 68. A screw shaft 69 having two sets of opposite threads 70 and 71 passes through the apertures of the nuts. A handwheel 72 is fixed to the upper end of the screw shaft and when rotated causes the movable plate to be displaced relative to the fixed plate. This arrangement provides for cross-leveling of the base ring transversely of the drawbar. When the caisson is unlimbered the drawbar is leveled by a prop 73.

A pair of spaced lugs 74-74 on the movable plate 60 are adapted to receive any one of the spokes 6 when the base ring is mounted on the post 59.

When the gun mount is carried by the caisson or other vehicle the gunner may fire upon aircraft to give protection to convoys and troops on the march. For the protection of fixed points the gun mount is removed from the vehicle and emplaced on the ground in a location affording a good field of fire.

The gunner occupying the seat places his feet on the base ring and by pushing against the ring moves the top carriage in azimuth. By acting on the handles of the cradle the gun is directed freely and quickly in elevation.

We claim:

1. A gun mount comprising a base ring, spokes in the base ring, a hollow pintle at the hub of the base ring, a support, a movable plate fixed to the support, a post on the support, a base ring having a hollow pintle mounted on the post and including means for engaging the spaced lugs, and a gun carriage rotatably mounted on the pintle.

the spokes, a top carriage including spaced standards and a cross-piece connecting the lower ends of the standards and pivotally mounted on the pintle, a seat carried by the cross-piece and arranged so that the feet of an occupant of the seat will engage the base ring whereby the top carriage is rotated, a cradle having spaced arms on the rear end trunnioned in the standards, an equilibrator between the top carriage and cradle, and a depending handle on each arm of the cradle whereby the cradle is moved on its trunnions, and a trigger-actuating linkage carried by the cradle.

2. A gun mount comprising a base ring, spokes in the base ring, a hollow pintle at the hub of the base ring, a support, a movable plate fixed to the support, a post on the support, a base ring having a hollow pintle mounted on the post and including means for engaging the spaced lugs, and a gun carriage rotatably mounted on the post and including spaced standards and a cross-piece connecting the lower ends of the standards and pivotally mounted on the pintle, a seat carried by the cross-piece and arranged so that the feet of an occupant of the seat will engage the base ring whereby the top carriage is rotated, a cradle having spaced arms on the rear end trunnioned in the standards, an equilibrator between the top carriage and cradle, and a depending handle on each arm of the cradle whereby the cradle is moved on its trunnions.

3. A gun mount comprising a base having an annular foot-engageable portion, a top carriage pivotally mounted on the base and including spaced standards, a seat on the top carriage arranged so that the feet of an occupant of the seat will engage the foot-engageable portion of the base whereby the top carriage is rotated, a cradle having spaced arms on its rear end trunnioned in the standards, an equilibrator between the top carriage and cradle, and a depending handle on each arm of the cradle whereby the cradle is moved on its trunnions.

4. A gun mount comprising a base having an annular foot-engageable portion, a top carriage pivotally mounted on the base and including spaced standards, a seat on the top carriage arranged so that the feet of an occupant of the seat will engage the foot-engageable portion of the base whereby the top carriage is rotated, a cradle trunnioned at its rear end in the standards, an equilibrator between the top carriage and cradle and a depending handle on the cradle operable by an occupant of the seat whereby the cradle is moved on its trunnions.

5. In a gun mount, a support, a plate fixed to the support, a movable plate hinged to the fixed plate, means for moving the movable plate about its hinge and holding it in position, a post on the movable plate, spaced lugs on the movable plate, a gun having a hollow pintle mounted on the post and including means for engaging the spaced lugs, and a gun carriage rotatably mounted on the pintle.

ELMER C. GOEBERT,
GEORGE W. BEATTY.

1. A gun mount comprising a base ring, spokes in the base ring, a hollow pintle at the hub of the base ring, a support, a movable plate fixed to the support, a post on the support, a base ring having a hollow pintle mounted on the post and including means for engaging the spaced lugs, and a gun carriage rotatably mounted on the pintle.
